UNITED STATES PATENT OFFICE.

WILLIAM ORR, OF TRENTON, NEW JERSEY.

METALLIC LATHING.

SPECIFICATION forming part of Letters Patent No. 425,245, dated April 8, 1890.

Application filed March 20, 1889. Serial No. 303,983. (No model.)

To all whom it may concern:

Be it known that I, WILLIAM ORR, a citizen of the United States, residing at Trenton, county of Mercer, and State of New Jersey, have invented certain new and useful Improvements in Metallic Lathing, fully described and represented in the following specification and the accompanying drawings, forming a part of the same.

10 This invention relates to a means for supporting metallic lathing either of the character known as "wire-cloth" or "wire-netting" lathing or lathing made from sheet metal suitably treated to provide for retaining the plaster thereon.

15 The means constituting the present invention is applicable both for the supporting of the lathing for ceilings or overhead work and for partitions or vertical work generally.

20 In order to convey a full understanding of the invention, it will now be described in detail, reference being had to the accompanying drawings, which illustrate the application of the invention in various forms both to over-

25 head work and to vertical work, and in which—

Figure 1 is a sectional view showing the invention applied in one form to overhead work. Figs. 2 and 3 are enlarged views of portions of Fig. 1. Figs. 4 and 5 illustrate modifications, which will be hereinafter referred to. Fig. 6 is an enlarged section taken on the line 6 of Fig. 1. Figs. 7 and 8 illustrate further modifications in overhead work, which will be hereinafter referred to. Figs. 9 and 10 illustrate still other modifications. Fig. 11 illustrates another modification in overhead work, also one application of the invention to vertical or partition work. Fig. 12 is a horizontal section taken on the line 12 of Fig. 11. Fig.

40 Fig. 13 is a section taken on the line 13 of Fig. 11. Figs. 14, 15, and 16 illustrate other modifications, which will be hereinafter referred to. Fig. 17 is a section on the line 17 of Fig. 14.

Referring now particularly to Figs. 1 to 8, 45 it is to be understood that A represents the ordinary iron I-beams for supporting the ceiling of a room and the floor of the room above, B planks resting upon the tops of and extending longitudinally of said beams, and C 50 D flooring planks and boards resting upon the planks B.

E represents the metallic lathing to which the plaster is applied for the ceiling of the room, which lathing may consist of wire cloth or netting, or may be sheet-metal lathing of any of the ordinary forms. The beams A are placed at such distances from each other that it is necessary to provide supports for the lathing material between the beams in order to make the lathing sufficiently rigid to enable it to properly receive and support the plaster. For this purpose I provide a series of supporting-rods a, which extend from beam to beam and are located at such distances from each other lengthwise of the beams as to afford the proper support for the lathing. In ordinary cases each of the rods a is provided at one end with a hook 2, which hooks over the flange at the lower edge of one beam, and at its opposite end either with a similar hook 3, (see Fig. 4,) by which it is secured to the flange of the adjacent beam, or is threaded and provided with a nut 4, which engages with a clip 5, by which the rod is secured to the flange of the beam.

If it is not desired to offset the rods a from the beams A, the hooks 2 may be of the form shown at the left of Fig. 10, and the clips 5 of the form shown in Fig. 5 and at the right of Fig. 10. In most cases, however, it will be preferable to offset the rods a more or less from the beams A, so as to provide spaces above the lathing E and beneath the beams to secure the proper locking of the plaster and an air-space. For this purpose there are provided offsetting-clips 6, of the form best shown in Fig. 3, which are inserted between the beams and the hooks 2, and extending beneath the beams serve to maintain the rods at a short distance from the lower sides of the beams. To accomplish the same result at the opposite ends of the rods, the clips 5 are preferably formed as best shown in Fig. 2—that is to say, they are provided with openings through which the rods a pass and with extensions which abut against the under sides of the beams, so as to offset the rods, the clips 5 thus constituting offsetting and attaching clips. The clips 5 6 may extend the entire length of the beams A, or they may be comparatively short, as indicated in Fig. 6. In either case the clips and rods a having

been placed in position the rods will be secured firmly to the beams by tightening the nuts 4 against the clips 5.

In those cases where it is desirable to dispense with the nuts 4 and the screw-threads upon the rods *a* the rods may be provided at the ends corresponding to their threaded ends with hooks 3, as shown in Fig. 4, between which and the clips 5 wedges 7 will be driven, so as to properly tighten the rods. In such case the shape of the offsetting and attaching clips 5 will be slightly modified, so as to retain the wedges in position, as indicated in Fig. 4. It is evident that with a nut or wedge to draw the rods taut comparatively small ones can be made to support as much weight without deflection as the heavy and cumbersome angle-iron or channel bars heretofore used for this purpose, and that they can be much more easily and quickly applied.

The lathing E may be secured to the rods *a* in any suitable manner. This may be accomplished by lacing the lathing at intervals to the rods, as indicated in Figs. 1 and 6, or sheet-metal clips may be employed to fasten the lathing to the rods, or the lathing may be formed with offset portions or loops at intervals, as indicated in Fig. 7, through which the rods can be inserted so as to pass between certain of the wires of the lathing, and in some cases the rods may be incorporated with the lathing in the process of weaving the same. In the case of sheet-metal lathing loops 8 may be struck up from the material of the lathing, through which the rods will be passed so as to secure the lathing thereto, as indicated in Figs. 14 and 17.

Where the plaster of a ceiling is quite thick and heavy or the spaces between the beams unusually wide, it may in some cases be necessary in order to prevent the rods *a* from sagging to provide intermediate supports for said rods between the beams A. Where this is necessary, it can readily be accomplished in the manner shown in Figs. 1, 2, 4, 9, and 10. For this purpose there are provided supporting or stay rods *b*, which may be comparatively light rods. These rods either pass under the rods *a*, about midway between the beams A, or are otherwise suitably secured thereto, and thence pass upward in opposite directions and over the tops of the beams A, being provided at their ends with hooks 9, (see Fig. 4,) by which they are secured to the flanges of the beams. In passing above the beams A these rods of course pass through the planks B, which are provided with suitable openings for the purpose, the planks being secured in their position upon the tops of the beams by means of side clips 10, which lock under the flanges of the beams.

In some cases it may be preferable to make the rods *a* in two or more parts, as indicated in Fig. 10, which parts are hooked together or otherwise connected at their meeting ends about midway of the beams A. The rods *b*

may also be made in two parts, which are hooked or otherwise connected to the rods *a*, as also indicated in said figure. As indicated in Fig. 10, the rods *a* are not offset from the beams A, but it is of course apparent that the rods *a* may be offset in this construction in the same manner as already described.

In some instances it may not be feasible to employ the clips 5 6 or to provide the rods *a* with tightening-nuts, as already described, and in such cases the rods may be provided at their opposite ends with hooks 12 of the form indicated in Fig. 9, which will engage with the adjacent flanges of the beams A, and in this case the rods *a* will be sprung into position between the beams, so as to be maintained there by the hooks 12. The hooks 12 may be formed so as to offset the lathing 85 from the lower sides of the beams or the lathing may rest against the lower sides of the beams.

In the construction shown in Figs. 1 to 4 the stay-rods *b* are only designed to support the weight of the plaster to prevent the rods *a* from sagging. It sometimes may be desirable to so arrange the rods *b* that they will prevent the lathing from yielding during the operation of applying the plaster, and this may be accomplished in the manner indicated in Fig. 9, in which case the rods *b* are connected to eyes formed upon the rods *a* and are provided at their upper ends with nuts by which they are secured to clips 13, which fit over the upper sides of the beams A. By this means the rods *b* serve to support the rods *a* and the lathing in both directions.

In many cases it is desirable, in order to provide greater security against the spread of fire in a building, to provide a second coat or partition of plaster located between the plaster of the ceiling and the floor of the room above, and in such case it is also preferable to so locate the ceiling and the intermediate plaster as to provide an air-space between the two and also between the intermediate plaster and the floor above. Where this is desired, it can readily be accomplished in the manner indicated in Figs. 1, 2, 3, and 7. For this purpose the upper sides of the beams A support a series of rods *c*, similar to the rods *a* and attached to the beam in a similar manner. In this case, however, the rods *c* need not be offset from the beams, and are consequently connected at one end by a hook 2, similar to the hook 2 of Fig. 10, and at the other by a nut and clip 4 5, similar to the nut and clip of Figs. 5 and 10. The lathing F is secured to the rods *c* in either of the ways before described.

In some cases it may be preferable to provide the intermediate partition of plaster in the form of arches extending between the beams, as indicated in Fig. 7, and in this case the rods *c* can be sprung in between the beams so as to assume the arched form shown in said figure, where they will be retained by their own elasticity without other fastening

means. The lathing *F* may be placed either above or below the rods *c*, as preferred.

In forming arched ceilings the rods *a* and their fastening-clips may be entirely omitted, 5 the plastered arches between the beams being supported by the rod *c*, as indicated in Fig. 7. In this case the lathing will, of course, preferably be upon the under side of the rods *c*. When the ceiling is formed in this manner, it will of course be desirable to provide coverings to conceal the lower sides of the beams *A* and to protect them from the action 10 of heat in case of fire, and for this purpose the lathing *F* will be extended from one arch to another around the lower sides of the 15 beams, as indicated in Fig. 8, it being supported by rods *d*, which extend around the lower sides of the beams and are connected at their ends to the rods *c* by hooks or otherwise.

If it is desired to offset the rods *d* from the lower sides of the beams, wedges 14 may be introduced between the beams and the rods, so as to hold the rods at a proper distance 25 from the beams and at the same time properly tighten them.

In some cases it may be impracticable, owing to the location of the beams *A*, to employ the hooks and clips of the form which has been 30 described for securing the rods *a*. Where such conditions exist, the rods may be supported in the manner indicated in Figs. 11 and 13, in which case the beams are provided with clips for retaining the rods, which are 35 composed of hangers 15, located upon the opposite sides of the beams and engaging with their flanges, and connected together beneath the beams by tie-bolts 16, which pass through openings in the hangers and through tubular 40 braces 17, located between the hangers to sustain them against the strain of the bolts. The portions of the hangers extending below the bolts 16 are provided with openings to receive the rods *a*, in which openings the rods 45 may be held by nuts 4, screwed onto their threaded ends, as indicated in Figs. 11 and 13; or the lower ends of the hangers may form nuts having right and left threads, into which the ends of the rods correspondingly threaded 50 are screwed.

What has been said in regard to overhead work also applies for the most part to walls or partitions where the studding is composed of beams of **I** or **T** form. The present invention may, however, be applied with good results to walls or partitions, or even ceilings made of solid masonry, or where wooden studding or beams are employed. In case of masonry walls or ceilings the rods *a* may be 55 secured to metallic furring-strips *f*, which in this structure are the equivalent of the flanges of the beams. The ends of the strips *f* may be embedded in the masonry, as indicated in Fig. 11, the strips projecting a sufficient distance from the walls to allow the rods to be secured by clips and hooks 25, the same 60 as to the flanges of the beams, as already de-

scribed; or the rods may be provided with clips 5 at each end, which clips form nuts, into which the rods are screwed by right and left screw- 70 threads formed on their opposite ends, as indicated in Fig. 12. The furring-strips *f* will, in case of a wall, preferably be arranged vertically, so that the rods *a* will extend horizontally; but this order may be reversed, and in 75 some cases the furring-strips instead of being embedded in the masonry may be fastened to it otherwise, being properly braced to resist the strain of the rods *a*.

The furring-strips *f* instead of being of 80 metal may be of wood, as indicated in Figs. 15 and 16, the edges of the strips being properly beveled to retain the hooks 2 and clips 5, this structure also being the equivalent of 85 the flanges of the beams.

The wooden strips *f* may be secured to the wall or ceiling in any suitable manner—as, for example, by nails or screws—and they may be properly braced to resist the strain 90 of the rods *a* by cross-pieces *g*, introduced at proper intervals, as shown in Fig. 16.

This construction possesses the advantage of providing isolated dead-air spaces between the strips *f* and cross-pieces *g*, which will retard the spread of fire and afford protection 95 against heat and cold. Cornices may be formed where required, in the manner indicated in Fig. 11, by oblique rods *h*, having their upper ends attached to one of the hangers 15, or in any other suitable manner to 100 the overhead beam or the rods *a*, their lower ends being embedded in the wall or partition or secured thereto by nails or screws, as indicated. The lathing will be secured to the rods *h* in either of the ways already described. 105

What I claim is—

1. The herein-described means for supporting metallic lathing, consisting of a series of rods extending from one to another of adjacent beams and secured at their opposite ends to 110 the flanges of said beams, and means for adjusting the tension of the rods, substantially as described.

2. The herein-described means for supporting metallic lathing, consisting of a series of 115 rods extending from one to another of adjacent beams and adjustably secured at their opposite ends to the flanges of said beam, and tightening-nuts for adjusting the tension of the rods, substantially as described. 120

3. The combination, with the beams of a ceiling or wall, of a series of rods hooked around the flange of one beam, and having an adjustable connection with the flange of the adjacent beam, whereby the tension of 125 the rods may be adjusted, and the metallic lathing secured to said rods, substantially as described.

4. The combination, with the beams of a ceiling or wall, of the rods *a*, hooked around 130 the flange of one beam and secured by clips to the flange of the adjacent beam, and the metallic lathing secured to said rods, substantially as described.

5. The combination, with the beams of a ceiling or wall, of the rods *a*, hooked around the flange of one beam, clips for securing the other ends of the rods to the flange of the adjacent beam, an adjustable connection between the rods and clips, and the metallic lathing secured to said rods, substantially as described.

6. The combination, with the beams of a ceiling or wall, of a rod hooked at one end around the flange of a beam and screw-threaded at the other end, a clip attached to the flange of the adjacent beam and provided with an opening to receive the threaded end of the rod, a nut for adjusting the tension of the rod, and the metallic lathing secured to the rod, substantially as described.

7. The combination, with the beams *A*, of the rods *c*, extending from one to another of the adjacent beams and sprung into position between said beams, and the metallic lathing secured to said rods and forming an arch, substantially as described.

8. The combination, with the beams of a ceiling or wall, of the rods *a*, extending from one beam to the adjacent one, the offsetting clips secured to the flanges of the beams for holding the rods away from the beams, and the metallic lathing secured to said rods, substantially as described.

9. The combination, with the beams of a ceiling or wall, of the rods *a*, extending from one beam to the adjacent one, the offsetting and attaching clips *b*, by which the rods are attached to the flange of a beam and held away from said beam, and the metallic lathing secured to said rods, substantially as described.

10. The combination, with the beams of a ceiling or wall, of the rods *a*, extending from beam to beam, the stay-rods *b*, connected to the rods *a* intermediate of the beams and hooked over the upper flanges of the beams on opposite sides of the connection with the rods, and the metallic lathing secured to the rods *a*, substantially as described.

11. The combination, with the beams of a ceiling or wall, of the rods *a*, extending from

beam to beam, the stay-rods *b*, connected to the rods *a* intermediate of the beams and secured to the adjacent beams, means for adjusting the tension of the stay-rods, and the metallic lathing secured to the rods *a*, substantially as described.

12. The combination, with metallic lathing provided with loops, of supporting-rods passed through said loops and provided with tension-adjusting means at one or both ends, substantially as described.

13. The combination, with the beams of a ceiling or wall, of supporting-rods extending from beam to beam and provided with tension-adjusting means at one or both ends, and the metallic lathing provided with loops through which the rods are passed, substantially as described.

14. The combination, with the beams of a ceiling or wall, of the rods *a*, extending from beam to beam on one side, the rods *c*, also extending from beam to beam, and the metallic lathing *E F*, secured to the respective rods with space between the two, substantially as described.

15. The combination, with the beams of a ceiling or wall, of the rods *a*, extending from beam to beam on one side, the rods *c*, also extending from beam to beam, the metallic lathing *E F*, secured to the respective rods with space between the two, and the stay-rods *b*, connected to the rods *a* intermediate of the beams and to the opposite sides of the beams, substantially as described.

16. The combination, with the beams of a ceiling or wall, of the rods *a*, extending from beam to beam on one side, the rods *c*, sprung between the beams to form arches, and the metallic lathing secured to the respective rods, substantially as described.

In testimony whereof I have hereunto set my hand in the presence of two subscribing witnesses.

WILLIAM ORR.
